(57) **CLAIM**

The ornamental design for a kiosk for recycling electronic devices, as shown and described.

DESCRIPTION

FIG. 1 is a front plan view of a kiosk for recycling electronic devices.

FIG. 2 is a front top perspective view of a kiosk for recycling electronic devices.

FIG. 3 is a side view of a kiosk for recycling electronic devices.

FIG. 4 is a rear top perspective view of a kiosk for recycling electronic devices.

FIG. 5 is a side view of a kiosk for recycling electronic devices.

FIG. 6 is a bottom plan view of a kiosk for recycling electronic devices; and,

FIG. 7 is a bottom plan view of a kiosk for recycling electronic devices.

The broken line showing is for illustrative purposes only and forms no part of the claimed design.
